US00D985323S

(12) **United States Design Patent** (10) Patent No.: **US D985,323 S**
 Tsutsui et al. (45) Date of Patent: ** May 9, 2023

(54) BEVERAGE MAKING MACHINE

(71) Applicants: **FUJI ELECTRIC CO., LTD.**,
 Kawasaki (JP); **SEVEN-ELEVEN**
JAPAN CO., LTD., Tokyo (JP)

(72) Inventors: **Takayuki Tsutsui**, Tokyo (JP); **Takuya Koyanagi**, Kounosu (JP)

(73) Assignees: **FUJI ELECTRIC CO., LTD.**,
 Kawasaki (JP); **SEVEN-ELEVEN**
JAPAN CO., LTD., Tokyo (JP)

(**) Term: **15 Years**

(21) Appl. No.: **29/801,961**

(22) Filed: **Aug. 2, 2021**

(30) Foreign Application Priority Data

Feb. 25, 2021 (JP) ..... 2021-003866 D

(57) CLAIM

The ornamental design for a beverage making machine, as shown and described.

DESCRIPTION

FIG. 1 is a front, right and top perspective view of a beverage making machine showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged end view with an internal mechanism omitted thereof, taken along the line 8-8 in FIG. 2.

1 Claim, 8 Drawing Sheets
